US00D978725S

(12) **United States Design Patent** (10) Patent No.: **US D978,725 S**
(45) Date of Patent: **** Feb. 21, 2023**

(54) **VEHICLE BODY**

(71) Applicant: **National Association for Stock Car Auto Racing, LLC**, Daytona Beach, FL (US)

(72) Inventors: **Brandon Thomas**, Concord, NC (US); **John Probst**, Concord, NC (US); **Eric Jacuzzi**, Concord, NC (US); **Christopher A. Popiela**, Concord, NC (US); **Timothy S. Murphy**, Concord, NC (US); **Donald E. Krueger**, Concord, NC (US)

(73) Assignee: **NATIONAL ASSOCIATION FOR STOCK CAR AUTO RACING, LLC**, Daytona Beach, FL (US)

(**) Term: **15 Years**

(21) Appl. No.: **29/753,863**

(22) Filed: **Oct. 2, 2020**

(51) LOC (14) Cl. **12-08**

(52) U.S. Cl.

USPC **D12/91**

(58) **Field of Classification Search**

USPC D12/86, 90, 91, 92, 164; D21/433, 434, D21/531, 532, 533, 534, 535

CPC B62D 25/00; B62D 25/06; B62D 33/00; B62D 35/00

(57) **CLAIM**

The ornamental design for a vehicle body, as shown and described.

DESCRIPTION

FIG. 1 is a perspective view of a vehicle body showing the new design;

FIG. 2 is another perspective view thereof;

FIG. 3 is a top plan view thereof;

FIG. 4 is a left side elevation view thereof;

FIG. 5 is a right side elevation view thereof;

FIG. 6 is a front elevation view thereof; and,

FIG. 7 is a rear elevation view thereof.

The broken lines illustrate features of the vehicle body that form no part of the claimed design.

1 Claim, 6 Drawing Sheets
